UNITED STATES PATENT OFFICE

HOWARD T. HALLOWELL, OF JENKINTOWN, PENNSYLVANIA, ASSIGNOR TO STANDARD PRESSED STEEL CO., OF JENKINTOWN, PENNSYLVANIA, A CORPORATION OF PENNSYLVANIA

STOOL

Application filed January 15, 1930. Serial No. 421,001.

My invention relates particularly to stools and chairs used in factories, although they can be used in other places without departing from the essential features of the invention.

One object of my invention is to make a very substantial yielding back for a stool or chair, and to so arrange the means which allows the back to yield, that one side of the back will yield to a certain extent independently of the other side, in order that it will readily accommodate the person who is using the stool, or other seat structure.

A further object of the invention is to pivot the back rest to the frame of the back section of the stool so that it will accommodate itself to the back of the occupant of the stool.

A still further object is to provide means for limiting the movement of the back section.

The invention also relates to certain details of construction described hereinafter.

In the accompanying drawings:

Fig. 1 is a side view of my stool, showing the improved yielding back;

Fig. 2 is a rear view of the stool;

Fig. 3 is a sectional plan view of the back rest on the line 3—3, Fig. 1;

Fig. 4 is a detached side view of the back rest;

Fig. 5 is a sectional view on the line 5—5, Fig. 2;

Fig. 6 is a sectional view on the line 6—6, Fig. 5;

Fig. 7 is a side view illustrating a modification of the invention;

Fig. 8 is a rear view of the modification shown in Fig. 7;

Figs. 9 to 12 are views illustrating further modifications of the invention; and

Fig. 13 is a sectional view illustrating a modification of the stop shown in Fig. 5, the section being on line 13—13, Fig. 7.

The stool shown in the drawings is made of steel pressed into shape.

Referring to the drawings, 1 is the seat proper, which is circular in the present instance, although it may be of other shapes

without departing from the essential features of the invention. This seat may either have

a metallic bottom section or a wooden bottom section, as desired.

2 are the legs, which in the present instance are angular in cross-section, and rungs 3, connect the legs and are made of sheet metal as illustrated and are secured to the legs by rivets or by welding. The legs are flared in the present instance, to form feet 4, which firmly support the stool on the floor.

The details of the stool described form no part of my present invention.

5 is the back of the stool. This back consists of two angular side members 7, which extend on either side of the stool and are pivoted to the two back legs 2 of the stool by pivot bolts 8, shown in detail in Fig. 5. The bolts are enlarged at 8a and this portion of the bolt extends through a hole in the side member 7 of the back but this enlarged portion is a greater depth than the metal of the side section, so that the bolt will act as a pivot for the back section. A nut 6 is mounted on the threaded portion of the bolt and secures the both firmly to the back leg 2 of the stool.

The upper ends of the side members of the back are connected together by a back rest 9, which is shaped as shown in Figs. 1, 2, 3 and 4, and the side members are also preferably connected by a cross piece 10, which is below the seat of the stool. The back section is yieldingly connected to the stool by two members, one at each side of the back, so that either or both sides will yield under pressure of the person occupying the stool. Bolts 11 extend through the side members 7 of the back and through perforations in the back legs 2 of the stool, and each bolt has a head 12 and on the bolt is a wing nut 13, in the present instance, and between the wing nut and the back leg of the stool is a spring 14, which yields when pressure is applied to the back. Surrounding the spring is a cup shaped stop 15, which limits the movement of the back, and the amount of movement can be regulated by the thumb nut. This cup shaped stop also acts to enclose the spring and limits the compression of the spring.

In Fig. 13 I have illustrated a modification of the stop shown in Fig. 5 and in this

instance the stop is in the form of a sleeve 15a, which is located between the bolt 11 and the spring 14.

The back rest 9, which connects the two side members 7—7 of the back section of the stool, has bearings 16 welded to its back and one arm 17 of each bearing is perforated for the passage of a rivet or other pivot 18, which not only connects the two side members 7 of the back but also allows the back rest to swing on said side members. In order to limit the amount of movement of the back rest, the bearings 16 have stop lugs 19 formed thereon, which come in contact with the side members 7 of the back section when moved to either extreme position. This back rest is curved as shown in Fig. 3, to accommodate the occupant's back and the edges are preferably rounded so as to provide a smooth surface. By this construction the back will not only yield under pressure but either side will yield to a certain extent independently of the other side, and the back rest will accommodate itself to the person using the stool.

Referring now to Figs. 7 and 8, the stool in these figures is the same as that shown in Figs. 1 and 2. The back section 5a of the stool, however, is made in the form of a U-shaped frame, as shown in Fig. 8, having an upper cross member 7b and side members 7a which extend down on either side of the stool and are pivoted to the two back legs 2—2 by bolts 8b. Each bolt is passed through a hole in one of the arms 7a and through a hole in the side flange of each rear leg 2. Above the pivot point of the arm 7a is a cross bar 10a, which is bent at each end to form angular members 10b, which are pivotally connected by rivets 20 in the present instance. The bolts 11a extend through the cross bar 10a and through holes in the rear legs 2 of the stool. On this bolt is a thumb screw and between this thumb screw and the back leg is a coil spring shown in detail in Fig. 13. In the upper end of each side member 7a of the back are a series of perforations 21, through one of which passes a pivot bolt 22, on which is a thumb nut 23. The bolt passes through bearings 16a on the back rest 9a and stop lugs 19a project from the said bearings 16a and limit the pivotal movement of the back rest. It will be noticed that the members of the back section are bent outwardly from the stool, so as to clear the seat of the stool, through preventing the back section from pinching the clothing of the occupant of the seat.

In Figs. 9 and 10 I have illustrated a modification in which the side member 7c of the back section has a right angle bent therein as at 24, so that while the major portion of the said side member is directly back of the leg, the lower portion rests against the side of the leg and is pivoted

thereto by a bolt 8c. In this instance the bolt 11c is in the form of an eye bolt. A pivot pin 25 passes through the eye of the bolt and connects the bolt with the side member 7c of the back. On the bolt is a wing nut, a coil spring and a stop similar to that shown in Fig. 5.

In Figs. 11 and 12 I have illustrated a still further modification in which the side members 7d are parallel with the sides of the rear legs 2 and are pivoted thereto by a bolt 8d. That part of each side member extending beyond the bolt is bent as at 7e so as to rest in front of the leg 2, and a headed bolt 11d extends through the leg and through the portion 7e of the side member, and has a wing nut thereon and a coil spring and stop similar to that illustrated in Fig. 5.

When it is desired to rigidly secure the back section to the legs of the stool or other seat structure, the bolts 11 and the spring and other parts are removed and a plain bolt and nut substituted therefor, which secures the back rigidly to the stool.

I claim:

1. The combination in a seat structure having legs, of a back section having side members; a bolt extending through each side member and through each back leg of the stool, each bolt being enlarged where it passes through the side member of the back section, the head of each bolt being spaced from its side member; and means for securing the bolt rigidly to the back leg of the stool.

2. The combination in a seat structure, of a seat member, legs supporting said member, a yielding back-rest comprising two upright and substantially rigid side members pivotally secured respectively to two of said legs at points below the seat, the securing means providing a loose fit and permitting independent movements of said side members so that when pressure is applied to one side of the back-rest that side may yield to allow the back-rest to assume a plane at an angle to the normal plane of said rest, springs resiliently supporting the back-rest in a forward position, and means associated with the legs and with the side members for limiting the rearward movement of said rest.

3. The combination in a seat structure, of a seat member, legs of angle section supporting said member, a yielding back-rest comprising two upright and substantially rigid side members of angle section, a flange of each of said side members lying flat against a flange of each of two of said legs, a bolt extending through both of the flanges of each contacting pair at points below the seat member and forming a loose connection between the said legs and uprights permitting independent movements of said side members, so that when pressure is applied to one side of the back-rest that side may yield to allow

the back-rest to assume a plane at an angle to the normal plane of said rest, a second pair of bolts extending through both of the flanges of each contacting pair at points intermediate the seat member and the first-named bolts, and a spring confined on each of said second bolts and exerting pressure upon the inner face of the leg flanges to resiliently maintain the back-rest in a normal advanced position.

HOWARD T. HALLOWELL.
